UNITED STATES PATENT OFFICE.

CARL F. HAAS, OF SOUTH BEND, INDIANA, ASSIGNOR TO WESTINGHOUSE ELECTRIC AND MANUFACTURING COMPANY, A CORPORATION OF PENNSYLVANIA.

DESIGN FOR A LAMP STANDARD.

Application filed March 6, 1929. Serial No. 30,351. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for Lamp Standards, of which the following is a specification, reference being had to the accompanying drawings, constituting a part hereof.

The figure is a view in perspective of a lamp standard.

I claim:

The ornamental design for a lamp standard substantially as shown.

In testimony whereof, I have hereunto subscribed my name this 28th day of Feb. 1929.

CARL F. HAAS.
